UNITED STATES PATENT OFFICE.

ROBERT T. WRIGHT, OF INDEPENDENCE, KANSAS.

HAY PRESS.

Application filed September 14, 1925. Serial No. 56,306.

To all whom it may concern:

Be it known that I, ROBERT T. WRIGHT, a citizen of the United States, residing at Independence, in the county of Montgomery and State of Kansas, have invented certain new and useful Improvements in a Hay Press, of which the following is a specification.

This invention relates to improvements in hay presses, and particularly to the type of hay press wherein a reciprocating plunger mechanism operates two plungers within a pair of aligned chambers for producing a double output in a machine normally having only a single output in the application of the same amount of power.

An object of the invention resides in providing a frame work with a pair of aligned compression chambers in which operate a pair of spaced plungers for compressing material within the chambers and between which plungers is positioned operating mechanism driving the plungers to compress material within the chambers which is of an adjustable character so that the timing of the stroke of operation can be varied in its relation to the operation of the other mechanism of the machine.

Another object of the invention resides in providing a press of the character above described, having rotary mechanism and adjustable connection between said rotary mechanism and a pair of spaced plungers at opposite sides thereof reciprocable in the compression chambers formed in the frame of the machine with which cooperate in timed relation, a mechanism on the top of the frame in the feed hoppers for the compression chambers for forcing the material in said hoppers into this compression chamber in timed relation with the operation of the plungers in order that the proper supply of material will be made into the compression chambers between each compression stroke of the plunger.

The invention further comprehends improvements in the particular construction and operation of the means for forcing the material into the compression chambers, together with the operating means for the plungers and associated mechanism therewith and also to mechanism for maintaining the slotted separating member for the bales in compressed relation against said bales

within the compression chamber until the baling wires have been applied.

The invention also comprehends improvements in the various details of construction and the arrangement of the parts shown and the above and other objects of the invention which are more particularly pointed out in the following detailed description and in the claims directed to a preferred form of the invention, it being understood however, that various changes in the size, shape and arrangement of the parts may be made for producing the same result, which constructions are clearly within the spirit and scope of the invention as herein set forth.

In the drawings forming part of this application—

Figure 1 is a side elevational view of the improved hay press.

Fig. 2 is an enlarged side elevational view of the central portion of the opposite side of the press from that shown in Fig. 1, showing particularly the details of construction of the feeding mechanism for forcing the hay into the compression chambers.

Fig. 3 is a plan view of the central portion of the machine.

Fig. 4 is a vertical sectional view taken on the line 4—4 of Fig. 3.

Fig. 5 is a detail perspective view of one of the plate members of the feeding mechanism.

Fig. 6 is a vertical longitudinal sectional view through the portion central of the press, showing particularly the plunger operating mechanism.

Fig. 7 is a horizontal sectional view thru a portion of one of the compression chambers illustrating the manner in which the plunger operates therein together with the mechanism for holding the material and the separating plates for the bale compressed in relation.

The improved hay press comprises a main frame 1 which is composed of a plurality of longitudinally extending bar members 2 mounted in spaced parallel relation and secured together by a plurality of transversely arranged frame members 3. This frame construction is supported upon trucks 4 and 5 respectively, the truck 5 being relatively rotatable on the frame for guiding the press when moved from place to place, which are

provided with the wheels 6. Each of these trucks are provided with suitable bracing members 7 while the pivoted truck 5 has a tongue mechanism 8 for connection with a tractor or the like, when it is to be moved from place to place.

Bottom forming members or plates 9 are positioned between the bottom frame bars 2 to form the bottom of the compression chamber for receiving and conveying material under compression therein and at spaced intervals from the central portion of the frame are hopper members 10, while the remaining outer end portions of the upper frame bars 2 have top forming plates 11 mounted therein in spaced parallel relation above the bottom plates 9.

The compression chamber is formed immediately below the hoppers 10 and the sides of the frame are closed by side members 12 at this point in order that the reciprocation of the plungers 13 will compress hay or other material fed into the compression chambers which are in spaced relation in the operation of the plungers in said chambers, so that bales of compressed material may be formed and forced outwardly toward the end of the frame between the top and bottom plates in compressed relation in a manner which will presently appear.

Referring particularly to Fig. 6 which clearly illustrates the plunger mechanism, it will be seen that the plungers 13 are substantially large block members slidably mounted in axial relation in the compression chambers formed below the hoppers 10 and reciprocate in their movement throughout the extent of the compression chambers and slightly beyond the terminus of the hoppers as shown at right hand end of Fig. 6, compressing material in the chambers. The upper ends or top portion of the plungers 13 are recessed as at 14 slidably receiving the movable plate member 15 which is slotted as at 16 in the central portion and the end portions of which slidably fit in said recesses 14. The central portion of this movable plate member 15 is provided with a pair of upwardly extending projections 17 at opposite sides thereof which carry rollers 18 adapted to ride on the upper surface of the frame bars 2 for supporting and guiding the movable plate mechanism in the operation of the plunger mechanism.

A suitable guard structure 19 is mounted above the frame bars 2 above the rollers 18 for preventing contact with the rollers in the operation of the plunger mechanism and also preventing loose material being compressed and from interfering with the operation of the movable plate members. Tongues 20 are mounted in recesses in the ends of the movable plate members 15 and project beyond the end portions thereof into

slots 21 extending longitudinally in the upper face of the plunger 13, and which tongues are retained in said slots by the cross members 22, carried by the plungers.

U-shaped members 23 are mounted on the adjacent ends of the plungers 13 as illustrated in Fig. 6, and have the leg portions thereof provided with a plurality of openings 24 for receiving the hinged ends 25 for the adjustable connecting rod mechanism 26. This connecting rod mechanism comprises a pair of sections 27 and 28, the section 27 being provided with a looped central portion mounted on the hinged end 25, while the section 28 comprises a substantially large looped portion 29 mounted in the annular recess of the cam 30. This cam 30 is provided with a pair of adjacent annular recesses for the member 28 of each connecting rod mechanism, while a suitable securing mechanism 31 serves to secure the end portions of the members 27 and 28 in assembled relation. This cam member 30 is eccentrically mounted on the shaft 32 which is rotatably mounted in the bearing bars 33 carried by the frame of the press.

On one end of the shaft 32 there is mounted the spur gear 34 with which meshes the reducing gearing 35 rotatably mounted on the stub shaft 36 carried by one of the bearing bars 33 while the shaft 37 mounts the drive pulley 38 provided with a spur gear for driving the reducing gearing 35, and in turn driving shaft 32 for operating the plunger mechanism.

The position of the hinge pins in the U-shaped bracket 23 adjusts the length of the stroke of the plunger 13 according to the position of said hinge pins in the openings 24 of said bracket, so that the operation of the machine may be varied within the desired limits.

Pairs of hook members 39 are pivotally mounted at opposite sides of each compression chamber in the frame member, and have the hooked ends 40 extending thru openings 41 in the side plates 12 carried by the frame. The end portions of these hooks project into the compression chamber as shown in Figs. 6 and 7, and serve to engage the material compressed in said chamber to retain the same in compressed relation outwardly of the hook and within the frame and also to retain the separating plates 42 at the outer end of the compression stroke so that the material will be retained in compression until baling wires can be inserted around the bales thru the slots 43 formed in the separating plates.

Bracket members 44 are mounted on the transverse frame forming bars 3 over the hooks 39 and form an abutment for coiled springs 45 encircling the guide pins 46 thereof which are adapted to normally retain the hooks 39 in the position shown in

Fig. 7. These springs bear upon the cross bar 47 extending between the hooks 39 and connected thereby by locking members 48 at the ends of the cross bar 47. It will be thus seen that the coiled springs 45 normally retain the pairs of hook members in operative position to retain material pressed by the plungers in compressed relation so as to hold the separating plates 42 while at the time being yieldable to permit the passage of the material being compressed as well as the operation of the plunger in moving the material beyond said hook.

15 The press is provided with a feeding mechanism, more particularly illustrated in Figs. 1 and 2 which includes a pair of uprights 50 mounted in spaced parallel relation on opposite sides of the frame and secured to 20 the frame bars 2, the end portions of which extend upwardly above the frame bars for rockably mounting the rock shaft 51 in the upper ends thereof which mounts an operating arm 52 on one end connected by the 25 pitman 53 with the crank pins 54 on the disks 55 mounted on the shaft 2, so that the rotation of said shaft, the rocking movement will be imparted to the rock shaft 51 for 30 operating the feeding mechanism for the press.

This feeding mechanism comprises a pair of spaced bar members 56 forming a rocking member and which bars are mounted in their central portions on the rock shaft 51 for 35 movement therewith. The end portions of the shaft are bent in angular relation and extend downwardly and between the free ends pivotally mount the plate members 57. The head 58 forming part of the plate 40 members or the portions pivotally mounted in the bar 56, are mounted so that the plate portions may be renewed when they become worn or broken without dis-assembling the 45 rocking member.

Levers 59 are pivotally mounted in their 50 central portions with between the bars 56 intermediate the central portion in the opposite end as clearly illustrated in Fig. 2, and have the lower ends connected by the 55 links 60 with the blade members 57 below the pivotal mounting in the bars 56. The upper ends of these levers 59 are connected by the coiled springs 61 which are constantly under tension. Ring members 62 forming 60 operating links are pivotally mounted on a cross bar 63 mounted in the uprights 50 and pivotally connected to the levers 59 below the pivotal mounting thereof between the bars 56, so that in the rocking of the rock- 65 ing member 56, the blade 57 will be caused to have a pivotal mounting in the rocking member so as to maintain the blades in a substantially upright position and produce a slight movement thereof toward the outer 65 end of the frame so that the blade mem-

bers will force the material within the hoppers as they move downwardly therein into the compression chambers in front of the plungers and slightly forward or outward toward the ends of the frame so that 70 the chambers will be completely filled with material and placed under slight compression. Suitable sleeves 64 may be mounted on the rock shaft 51 and also the rock shaft 63 as illustrated in Fig. 4, for maintaining 75 the rock member and the operating link 62 in proper operative position. U-shaped bracing members 65 have their free ends connected with the frame bars 3 and the central portions with the uprights 50 in order to 80 rigidly mount said uprights on the frame to prevent movement thereof in the operation of the machine.

A suitable guard plate 66 is mounted over the guard rails 19 in the operating mechanism for the plungers to prevent the material in the hoppers from fouling the mechanism thereunder.

In operation, the pulley 38 is rotated from a suitable motor, either mounted on the frame bars 2 or from a separate power unit by a belt connection which rotates the shaft 52 and operates the cam 30 which in turn produces a reciprocating movement of the plungers 13 in the frame and in the compression chambers which are supplied with material through the rocking operation of the rock member and the operation of the blades 57 for forcing materials into the hoppers 10 into the compression chambers in 100 timed relation so that the blades operate to force material into the compression chambers when the plunger of the particular chamber is in retracted position.

The plungers 13 through the operation of the cam will be drawn during one stroke of movement toward each other when the center of the cam is at right angles to the axis of the shaft 32 as compared with the longitudinal axis of the machine and will be separated or moved to a greater distance apart in 110 the position shown in Fig. 6 which is compensated for by the shortness of the plate 15 which forms a means of preventing the material to be compressed from falling from the hopper into the operating mechanism and thereby interfering with the efficient operation. This plate mechanism which is supported on the rollers 18 reciprocate 115 through the operation of the plunger.

At the outer limit of movement of each plunger 13, the end portion of the same engages the ends 40 of the hook members 39 and forces the same outwardly against the tension of the springs 45 so as to force material being compressed in the ends of the hook or to move one of the separating plates 42 beyond the hooks so that the material is retained in compressed relation while the plunger is withdrawn for receiving a new 130

charge of material in the compression chamber.

The plungers 13 are alternately moved thru their compression stroke as will be clear from Fig. 6, it will be seen that only sufficient power is necessary for operating one of the plungers which is taken advantage of for operating a double compressing mechanism mounted in axial alinement and 10 operating in opposite directions for increasing the production of one machine.

The position of the disk member 55 on the shaft 32 is such that the rock member formed by the bars 56 will be operated in 15 such timed relation with the plunger 13 that the blades will be moved downwardly and outwardly toward the end portions through the operation of the link 62 for supplying material within the hoppers to the compression chambers when the plungers are in their retracted positions.

It should thus be appreciated that substantially efficient yet simple machine construction has been provided for producing a 25 hay press in which substantially novel structures exist in the operation of the plunger mechanism and the construction and operation of the machine feeding mechanism together with the hook members for holding 30 the material in compressed relation.

It is to be understood that the brace members 7 are preferably removable in order that they may be removed at one end when it is desired to move the machine from place to 35 place to permit steering. In view of the braces at both ends being removable, the machine may be moved in either direction without turning it around for the purpose.

Having thus described my invention, what 40 I claim as new is:—

1. A hay press comprising a frame structure provided with a pair of baling chambers, a pair of plungers operating in axial alinement in said baling chambers, and operating mechanism between said plungers including bracket members mounted on said plungers, a shaft rotatable in said frame work between said plungers, an eccentric mounted on said shaft and connecting rod 45 mechanisms mounted on and operable by said eccentric having adjustable connection with the bracket members on said plungers, and operating means for rotating said shaft.

2. A hay press comprising a frame structure provided with a pair of axially alined baling chambers, a pair of plungers operable in alinement in said chambers for compressing material therein, operating mechanism for said plungers including rotatable 55 means between said plungers mounted for rotation in said frame structure, connecting rod members operable by said rotatable means having adjustable connections with said plungers for operating the plungers to 60 produce a reciprocating movement thereof

in the rotation of said rotary means, power operated means for rotating said rotary means, and a movable plate mechanism suspended for sliding movement on said frame work having the ends slidably received in 70 recesses in said plunger.

3. A hay press, comprising a frame structure, spaced uprights mounted on said frame structure, compression chambers in said frame structure having inlets in the top portion of the frame, and feeding mechanisms in said uprights above said frame structure including a rocking member, blade members pivotally mounted in said rocking member, operating connections between said rocking member and an operating means for producing a rocking movement of the rock member in the operation of said operating means, and mechanism connected with said uprights and said blade members for producing a pivotal movement thereof in the rock member in the rocking movement thereof, said blade members being adapted to force material through the inlet openings into the compression chambers in the operation of 90 the rocking members.

4. A hay press comprising a frame structure provided with a pair of baling chambers, plungers operable in said baling chambers for compressing material therein, power operated means for operating said plunger, and a feeding mechanism for feeding material to be compressed into the compression chambers including a rock shaft, operating connections between said power operated means to the rock shaft, for producing a rocking movement thereof, a rock member mounted in its central portion on the rock shaft and movable therewith, blade members pivotally mounted in the ends of the rock member, levers mounted in said rock member, coiled springs connecting similar end of said lever, link connections between the opposite ends of said lever and said blade members, and operating links connected with said lever and a portion of the frame structure of the press, whereby in the rocking movement of said rock member its pivotal movement of the blade members is effected through the operation of said operating links and the levers and the connecting links with said blade members, so that material is effectively forced into the compression chambers for subsequent compression by the operation of said plungers.

5. A feeding mechanism for hay presses; wherein the hay press includes a frame structure, spaced uprights mounted on the frame structure, compression chambers in said frame structure having inlets in the top portion thereof, and operating means carried by the frame structure; comprising a rocking member mounted in said uprights for rocking movement, connections between the rocking member in the operating means 125

for producing a rocking movement of said member in the operation of said operating means, blade members pivotally mounted on said rocking member and adapted to enter said compression chambers in the rocking movement of said members, and means interconnecting said blade members and having portions attached to said uprights for simultaneously rocking said blade members on said rocking member in the operation thereof, adapted to feed material into the compression chambers to said inlets. ¹⁰

In testimony whereof I affix my signature.

ROBERT T. WRIGHT.
